FOLDING CHAIR

Emil C. Hake, St. Louis, Mo.

Application December 20, 1950, Serial No. 201,727

1 Claim. (Cl. 155—148)

1

This invention relates to folding chairs as designed for conventional use, and the main object of the invention is to provide a folding chair including a seat, legs and back, so constructed and assembled together in unitary form that these elements may be easily and readily folded up together when not in use, in very compact form for storage or transportation, and likewise may be quickly and easily opened out and set up for use as occasion may require.

Another object of the invention is to provide a folding chair including seat, legs and back members foldably connected together, the seat member being flanged downwardly around its margins to form and provide a shallow compartment within which the legs and back may be compactly folded together for storage, the pairs of legs at front and back respectively being rigidly connected in spaced relation to move as a unit, and as such units being pivotally connected at front and back within the pendant marginal flanges of the seat, brace-frames pivotally connected to the leg units at front and back in spaced relation to their upper ends and arranged to swing inwardly at their free ends to the central portion of the seat at the under side thereof, means at the central under side portion of the seat for releasably locking the free ends of said brace-frames to the seat for rigidly supporting the legs in open position relative to the seat as required in use, the said back being so pivotally connected at its lower end within the pendant marginal flanges at each side of the seat as to enable the seat to fold completely down and inwardly of the under side of the seat, or to turn vertically outward and upward as required in use, and means for releasably locking the said back in its open and vertically extended position for use, the rear marginal flange of the seat being slotted out at its ends to enable the described complete pivotal movements of the back.

With the stated objects in view, together with such other and additional objects and advantages as may appear from the specification and claims, attention is now directed to the accompanying drawings as exemplifying a preferred embodiment of the invention, and wherein:

Figure 1 is a frontal elevation of the chair as set up and opened out for use.

Figure 2 is a sectional side elevation, taken on the line 2—2 of Figure 1.

Figure 3 is a rear elevation of the chair as set up and opened out for use.

Figure 4 is a horizontal cross section, on the line 4—4 of Figure 1.

Figure 5 is an under side view of the seat, showing the legs or leg-frames as folded down within the shallow compartment formed by the marginal flanges of the seat, and showing the chair back as released from its operative position relative to the seat and extended out in alignment with the seat, in the process of folding the elements up together in compact form for storage or transportation.

10 Figure 6 is an under side view of the elements of the chair as folded up compactly together for storage or transportation.

15 Figure 7 is a perspective view of the elements of the chair as folded up compactly together as shown in Figure 6, but in reversed position end for end as to Figure 6.

Figure 8 is a horizontal cross section, on the line 8—8 of Figure 3.

20 Figure 9 is a horizontal cross section, on the line 9—9 of Figure 3.

Figure 10 is a cross section on the line 10—10 of Figure 4.

In practising this invention I provide a rectangular seat 5, the same being formed of any suitable material, and having pendant marginal flanges 5a for forming and providing a shallow compartment 5b within which the frontal legs 6 and rear legs 7 together with their respective brace-frames 8, 13, and the back-frame 16 with its locking frame 17, may be compactly folded for storage or transportation.

A pair of frontal leg-lugs 6a are mounted at the under side of the seat 5, in slightly spaced relation to the lateral flanges 5a of the seat, whereby the frontal legs 6 may be seated within the space between the lugs and flanges, and may be then pivotally anchored in place by means of heavy rivets 10 passed freely through the upper ends of the lugs and anchored at their ends in the lugs and flanges.

A brace-frame 8 is provided for the frontal legs 6, the same including a flat and narrow cross bar 8a of a length nicely to span and fit in between the frontal legs 6, and being formed at the ends with inturned tabs 8b, whereby this cross bar is pivotally mounted in place between these legs by passing pins or rivets 11 through the legs in spaced relation from their upper ends and through the inturned tabs 8b freely. A pair of flat and narrow side bars 8c are rigidly anchored at their outer ends onto the cross bar 8a, in substantially spaced relation and in transverse alignment, and a similar flat and narrow latch bar 8d is rigidly anchored at its ends onto the inner ends 55 of the side bars 8c, this said latch bar being tilted

3

so as to flatly contact the under surface of the seat 5 when the brace-frame 8 is swung up against the under side of the seat. A pair of flat lock-tongues 8e are rigidly extended in spaced relation from the inner margin of the latch bar 8d, these tongues being adapted to nicely yet freely seat within the space provided by the lock-lugs 8f which are rigidly mounted onto the under face of the seat 5 in triangular arrangement for providing the intermediate seating space 8g for the tongues 8e.

The rear marginal flange 5a of the seat 5 does not extend to or contact at its ends the ends of the side flanges of the seat, but these ends of the rear flange are turned perpendicularly inward as at 5d, for providing at each side of the seat open slots or recesses 12, thus forming sockets opening rearwardly for receiving the lower ends of the side bars of the chair-back, as provided and mounted in manner later described.

A pair of rear leg lugs 7a are mounted at the under side of the seat 5 in slightly spaced relation to the inturned ends 5d of the rear marginal flange 5a, for providing sockets for receiving the upper ends of the rear legs 7, which are pivotally pinned therein in manner later pointed out.

A brace frame 13, similar to the frontal brace frame 8, is provided for the rear legs 7, said brace frame including a flat and narrow cross bar 13a of a length nicely to span and fit in between the rear legs 7, and being formed at its ends with inturned tabs 13b, whereby this cross bar may be pivotally mounted in place between the legs 7 in manner later pointed out. A pair of flat and narrow side bars 13c are rigidly anchored at their outer ends onto the ends of the cross bar 13a in transverse alignment, and a similar flat and narrow latch bar 13d is rigidly anchored at its ends onto the inner ends of the side bars 13c, this said latch bar being also tilted so as to flatly contact the under surface of the seat 5 when the brace frame 13 is swung up against the under side of the seat. A pair of flat lock tongues 13e are rigidly extended in spaced relation from the inner margin of the latch bar 13d, these tongues being formed and adapted to nicely yet freely seat within the space provided intermediately of the lock lugs 13f which are rigidly mounted onto the under face of the seat 5 in triangular formation for this purpose, said space being indicated at 13g.

With the described elements thus arranged and mounted, it will be seen by inspection of Figure 4 that there is a transverse space at the under side of the seat 5 intermediate of the brace frames 8 and 13, as indicated at 13h. A pair of elongated latches 14 are mounted centrally and in laterally spaced relation within this space 13h by passing screws 15 down through the centers of these latches and seating the screws into the under side of the seat 5. These latches are thus mounted medially of the space 13h and in alignment with the lock tongues 8e and 13e of the latch bars 8d and 13d, and the latches 14 are of such length that when they are turned perpendicularly to the latch bars the ends of the latches will slidably pass over and bear upon the lock tongues 8e, 13e, thus rigidly holding the brace frames 8 and 13 in place for firmly supporting the frontal and rear chair legs 6 and 7 in opened position for use of the chair. Likewise when the chair is not in use the latches 14 may be turned free of the tongues 8e and 13e for freeing the brace frames, after which the chair legs and brace frames may all be folded

down closely together within the compartment 5b at the under side of the seat 5. The supporting function of the brace frames 8 and 13 is clearly shown in Figure 2, where the rear frame is indicated in full lines as for supporting the rear legs, and in broken lines as released for folding up together with the other elements into the compartment 5b.

A chair-back frame 16 is provided, the same comprising a back-bar in the form of an inverted U, for providing a pair of spaced side-bars 16a, and a connecting top bar 16b, upon which is mounted a flat cross-plate 16c anchored at its ends to the side bars immediately below the top bar, and cut out centrally thereat to form a handle slot 16d. A lower cross slat 16e is likewise anchored at its ends to the side bars adjacent the lower ends thereof. Slide-loops 16f are mounted in both transverse and vertical alignment upon the outer sides of the cross plate 16c and cross slat 16e, and a latch frame 17 is slidably mounted through the slide-loops 16f of the cross plate 16c and cross slat 16e. For this purpose the latch frame 17 is constructed of three narrow and flat slats 17a adapted to pass slidably and freely through the slide-loops 16f. These slats are accordingly arranged side by side in suitable spaced relation for aligning with the slide-loops 16f, and are anchored together by means of flat cross-slats 17b at top, bottom and centrally as shown. The top and bottom cross-slats are formed with handle-slots 17c, the upper slot being positioned so as to register with the handle-slot 16d of the cross-plate 16c when the latch frame is drawn fully upward and into contact with the top bar 16b of the frame 16, in the use and operation of the chair. The bottom cross-slat of this latch frame is positioned somewhat above the lower slide-loops 16f of the cross-slat 16e of the chair-back frame 16, to enable this latch frame to be raised or lowered for the purpose of enabling this frame to function for releasably locking the chair-back frame 16 into upright position relative to the seat 5, in the use of the chair as such, and as will later be described.

The lower ends of the side bars 16a of the chair back frame 16 are offset outwardly as at 16g, and are thus seated within the sockets or recesses 12, as referred to in column 3, lines 12-20, inclusive. With the upper ends of the rear legs 7 also seated within the sockets between the leg lugs 7a and the inturned ends 5d of the rear marginal flange 5a of the seat 5, as pointed out in column 3, lines 12-20, inclusive, pivot bolts 18 are passed through all of these assembled elements, the same being suitably bored through for this purpose transversely, and whereby the rear legs and the chair-back frame and latch frame may all be pivotally turned down at the under side of the seat 5 when not in use, together with the frontal legs 6 as before described, this operation being facilitated by the offset lower ends of the side bars 16a, as indicated at 16g and which are pivotally seated within the sockets or recesses 12 formed and provided as aforesaid at the rear corners of the seat 5.

The rear brace frame 13 is pivotally mounted in place between the rear legs 7 by passing pins or rivets 19 through the legs in spaced relation from their upper ends and through the inturned tabs 13b freely, in manner similar to the pivotal mounting of the frontal brace frame 8. Thus means are provided for completely and compactly folding all of the described elements of

the chair down within the compartment 5b at the under side of the seat 5.

As means for releasably locking the chair-back frame 16 into its desired upright position relative to the seat 5, when the chair is opened out for use, the frame 16 is thus first raised and suitably positioned as for use. The latch frame 17 is then lowered so that the lower ends of the slats 17a of this frame rest upon the upper side of the seat 5, and laterally elongated slots 5f are then cut through the seat 5 to form and provide keeper-slots for receiving and passing the lower ends of the slats 17a. A suitably elongated keeper bar 20 is provided, the same being rectangular in cross section and formed with three narrow and flat sockets 20a elongated on the longitudinal axis of the bar, the same being of the same form and dimensions as the slots 5f of the seat 5 and likewise adapted to receive and pass the lower ends of the slats 17a when the latch frame 17 is lowered for the purpose of locking the chair-back frame 16 to upright position for use. This keeper bar 20 as thus formed is rigidly mounted onto the under side of the chair seat 5, transversely alongside the rear marginal flange 5a thereof, and so positioned that the sockets 20a thereof exactly align and register with the keeper slots 5f of the chair seat 5. When not in use the chair-back frame may be released by pulling upward on the latch frame, thus withdrawing the slats of the latch frame from the keeper sockets of chair seat and keeper bar, after which the legs, brace frames and chair-back frame may be all compactly folded down together within the compartment 5b at the under side of the seat. All as hereinbefore set out and described.

While I have herein shown and described a preferred embodiment of the invention, and preferred structural features thereof, it is understood that minor changes may be made as desired, in respect of the structures shown, provided such changes fall within the scope of the claim. If desired, and as here shown, the rear legs may be joined together at their lower ends, as clearly shown in the drawings, by means of the connected cross bar 7b.

I claim:

A foldable chair comprising a rectangular seat formed with pendant flanges at its margins to provide a shallow compartment at the under side thereof, frontal and rear leg units pivotally connected with the seat at front and back and arranged to fold up inwardly together within the said compartment at the under side of the seat,

brace frames pivotally connected to the frontal and rear leg units in spaced relation to the upper ends thereof and arranged to swing and fold inwardly at their free ends into the said compartment at the under side of the seat within the said compartment thereat for releasably locking the said brace frames to the seat for rigidly supporting the leg units in open position relative to the seat, for the purpose of adapting the chair to use, a chair-back frame pivotally connected at its lower side with the seat at the rear margin thereof, the said frame comprising a back-bar in the form of an inverted U for providing side and top bars, the side bars being pivotally connected at their lower free ends with the rear margin of the seat through recesses formed through the ends of the pendant rear flange of the seat, for enabling the chair-back frame to be raised to upright position at the upper side of the seat, and to fold down underneath the seat into the said compartment thereat, means for releasably supporting the chair-back frame in upright position at the upper side of the seat for adapting the chair for use as such, said means for supporting the chair-back frame in upright position at the upper side of the seat comprising cross members extended between the side bars of the chair-back frame, slide-loops mounted in both transverse and vertical alignment upon the outer sides of the cross members, and a latch-frame including spaced slats passed slidably through the slide-loops for perpendicular extension from the chair seat, cross slats anchored to the first mentioned slats for locking the unit together, and keeper slots cut through the rear margin of the chair seat for receiving the lower ends of the slats of the latch-frame as passed through the said slide-loops, for releasably locking the latch-frame in upright position for use, when so desired.
